UNITED STATES PATENT OFFICE.

ALBERT F. GEORGE, OF BISBEE, ARIZONA TERRITORY, ASSIGNOR OF ONE-HALF TO JOHN RYAN, OF KANSAS CITY, MISSOURI.

WINDMILL.

No. 880,518.

Specification of Letters Patent.

Patented March 3, 1908.

Application filed July 28, 1906. Serial No. 328,234.

To all whom it may concern:

Be it known that I, ALBERT F. GEORGE, citizen of the United States, residing at Bisbee, in the county of Cochise and Territory 5 of Arizona, have invented certain new and useful Improvements in Windmills, of which the following is a specification.

My invention relates to improvements in windmills.

10 The object of my invention is to provide in a windmill having a plurality of windwheels novel means for supporting the windwheels on a single tower in a manner such that the support carrying the wheels will be 15 evenly balanced as to the weight of the windwheels and the wind pressure upon them.

My invention provides further novel governing means for controlling the throwing into and out of the wind of the windwheels 20 carried by the revolving support.

Other novel features are hereinafter fully described and claimed.

In the accompanying drawings illustrative of my invention, Figure 1 is a front elevation view of my improved windmill, with the windwheels and vanes shown thrown out of the wind, the upper part only of the tower being shown. Fig. 2 is a plan view of what is shown in Fig. 1, some of the parts being 30 broken away and the pivoted vane being shown in dotted lines disposed transversely to the faces of the windwheels. Fig. 3 is a vertical central sectional view of the automatic means for locking the pivoted vane, 35 the vane shank being shown engaged.

Similar characters of reference denote similar parts.

1 denotes the ordinary tower having secured to its upper end a horizontal annular 40 plate 2 having in its upper side an annular ball race 3 having therein a series of balls 4 located also in a similar ball race in the under side of a horizontal annular plate 5 which supports upon its upper side a support or 45 truss 6 preferably constructed of steel bars joined together in the manner of an ordinary bridge truss. Rotatively mounted on the truss or support 6 are two pairs of horizontal shafts 7 disposed at opposite sides of a vertical plane intersecting transversely to the support 6 the axis of revolution of said support, 50 said plane being parallel also with the shafts 7. The shafts 7 of each pair are disposed at

opposite sides of a vertical plane intersecting the axis of revolution of the support 6 at 55 right angles to the transverse plane. The shafts of each pair have the same axis. Four windwheels 8 are secured respectively upon said shafts 7, and outside the support 6, the windwheels being disposed in two pairs 60 and the wind wheels of each pair being located one in front of the other.

The blades 9 of the windwheels of each pair are inclined in opposite directions, so that the wind passing through the forward 65 wheels will strike the rear wheels so as to rotate the rear wheels oppositely to the direction of rotation of the forward wheels.

To prevent "teetering" of the frame or support 6, corresponding windwheels of the 70 two pairs may have their blades inclined oppositely so that corresponding wheels will rotate in opposite directions.

Rotatively mounted on the support 6 in suitable bearings is a longitudinal horizontal 75 driving shaft 10 disposed in the vertical plane which intersects longitudinally the axis of revolution of the support 6. The shaft 10 is provided with a crank 11 to which is pivoted the upper end of a downwardly extending 80 pitman 12 which may be employed to operate a pump, not shown, or perform other desired service. The crank 11 is located at the intersection of the longitudinal and transverse planes above mentioned. 85

Opposite ends of the driving shaft 10 have secured thereon bevel gears 13 which mesh respectively with bevel gears 14 secured one to each shaft 7 at its inner end. By means of these gears movement in a like direction 90 is imparted to the driving shaft 10.

At one end of the support 6 intermediate the adjacent windwheels 8 is secured an auxiliary vane 15 disposed parallel with the shaft 10, and preferably in the same vertical 95 plane, the vane having its flat sides disposed parallel with the faces of the windwheels 8.

A steering vane 16 is pivoted on a vertical axis located in the central transverse vertical plane intersecting the axis of revolution of 100 the support 6. The vane 16 has secured to it a horizontal arm 17 extending rearward at an angle to the vane 16 and by means of which the vane is retracted to the position shown in dotted lines in Fig. 2, in which position the support 6 will be swung so that the 105

faces of the wind wheels 8 will be in the wind. The axis of the vane 16 is preferably a vertical bar 18 to which the vane is secured and which is rotatively mounted in suitable bearings in the support 6.

5 To swing the vane 16 to the position shown in dotted lines in Fig. 2, a flexible device such as a rope 19 has one end secured to the outer end of the arm 17, said rope passing over a 10 pulley 20 secured on the support 6 and having its lower end extending downward from said pulley and secured to a member comprising preferably a bar 21 one end of which is secured pivotally to the support 6. On 15 the bar 21 is secured a weight 22, which is adjustable lengthwise of the bar and is secured in position thereon by a set screw 23. The pressure of the weight normally, by bearing down on the rope 19, pulls the arm 20 17 so as to swing the vane 16 to the position shown in dotted lines in Fig. 2. To manually retract the vane 16 to the position shown in solid lines in Figs. 1 and 2, in which 25 position the wheels 8 will be thrown out of the wind, a rope 24 has one end secured to the shank of the vane 16 and passes therefrom horizontally against a pulley 25 rotatable on a vertical axis and supported on the support 6. The rope 24 passes thence 30 horizontally to a pulley 26 pivoted on a horizontal axis to the support 6, and thence downwardly through the central openings in the annular plates 2 and 5.

35 Releasable automatic locking means for holding the vane 16 in the position shown in solid lines in Figs. 1 and 2 are provided comprising preferably the following described mechanism, referring particularly to Fig. 3.

40 Upon the upper and rear side of the support 6 to the rear of the pulley 25 is a bracket 45 27 having two rearwardly extending horizontal arms 28 and 29 disposed one above the other and adapted to receive between them the shank 30 of the vane 6 when the vane is swung by the wind or manually to 50 the position shown in solid lines in Figs. 1 and 2. The lower arm 29 has on its underside a U shaped extension 31, the horizontal portion of which is provided with a vertical 55 hole in which is slidably mounted a locking bolt 32, the upper end of which extends through a vertical hole in the arm 29 and is beveled rearwardly and downwardly, as shown in Fig. 3, so that when the shank 30 60 of the vane 6 enters the bracket between the arms 28 and 29, the bolt 32 will be depressed to allow the shank to pass beyond said bolt. A coil spring 33 encircles the bolt 32, the lower end bearing upon the horizontal portion 65 of the extension 31 and the upper end bearing upon a transverse pin secured in a hole in the bolt 32 below the arm 29, said pin being denoted by the numeral 34. The tension of spring 33 is such that the bolt 32 is normally held in the position shown in Fig.

3. To manually release the shank 30 of the vane 6 from the locking mechanism, the upper end of a rope 35 is secured to the lower end of the bolt 32, said rope passing downward through the openings in the annular 70 plates 2 and 5 to a point where it may be grasped by the operator.

In operating the invention, when the rope 35 is pulled downward, the bolt 32 will be retracted and the weight 22 will then by 75 bearing down on the pivoted bar 21 draw the rope 19 downward and through the intermediacy of the arm 17, the vane 6 with its shank 30 will be swung toward the position shown in dotted lines in Fig. 2. The support 6 will then be swung by the wind pressure acting on vane 16 to a position in which the wheels 8 will be thrown into or facing the wind. The position taken by the support 6 will depend upon the position of the weight 22 on the bar 21, the weight of said weight, and the relative area exposed to the wind of the vanes 15 and 16, as well as upon the velocity of the wind blowing at the time. If the wind increases in velocity, the vane 15 85 will cause the support 6 to be swung so that the windwheels 8 will be thrown more out of the wind, and upon sufficient wind pressure which might damage the mill, the vane 15 will cause the support 6 to be swung so that the vane 16 will be automatically engaged by the locking mechanism hereinbefore described. This engagement may be manually made by drawing downward on the rope 24, in which 90 case, the vane 6 may be swung relative to the support 6 so that the shank 30 will enter the bracket 27 between the arms 28 and 29, and, by forcing downward the bolt 32 pass beyond the bolt and be held thereby, the bolt immediately being upwardly moved by the spring 100 33. By adjusting the weight 22 lengthwise on the bar 21, the governing of the position of the support 6 relative to the wind, and the speed of rotation of the windwheels 8 regulated to suit the purposes of the operator. 105 The length of the rope 19 should be such that the bar 21 will swing above and below a horizontal line intersecting the pivotal point of said bar.

110 My invention may be modified in different ways within the scope of the appended claims without departing from its spirit.

Having thus described my invention, what I claim and desire to secure by Letters Patent, is:—

1. The combination with the tower, of a support rotative thereon in a horizontal plane, two pairs of vertical wind wheels rotatively mounted on said support at opposite sides of a vertical plane intersecting transversely to the support the axis of revolution of the support, the wind wheels of each pair being disposed one in front of the other and at opposite sides of a vertical plane intersecting the axis of revolution at right angles to 125 130

the other intersecting plane, a pitman, and means by which rotation of said wind wheels is employed to reciprocate said pitman.

2. The combination with the tower, of a support rotative thereon in a horizontal plane, two pairs of vertical wind wheels rotatively mounted on said support at opposite sides of a vertical plane intersecting transversely to the support the axis of revolution of the support, the windwheels of each pair being disposed one in front of the other and at opposite sides of a vertical plane intersecting the axis of revolution at right angles to the other intersecting plane, a pitman, a rotary shaft having a crank pivoted to said pitman, and means by which rotation of said wind wheels rotates said shaft.

3. The combination with the tower, of a support rotative thereon in a horizontal plane, two pairs of vertical wind wheels rotatively mounted on said support at opposite sides of a vertical plane intersecting transversely to the support the axis of revolution of the support, the wind wheels of each pair being disposed one in front of the other and at opposite sides of a vertical plane intersecting at right angles to the other intersecting plane the axis of revolution, the blades of each wheel being inclined relative to the face of the wheel oppositely to the blades of the other wheel of the pair, a pitman, a rotary shaft having a crank pivoted to the pitman, and means by which the rotation of the windwheels imparts rotation in a like direction to said shaft.

4. The combination with the tower, of a support rotative thereon in a horizontal plane, a driving shaft rotatively mounted longitudinally on said support and intersecting the axis of revolution of the support and having at the axis of revolution of the support a crank, a pitman pivoted to said crank, two pairs of transverse horizontal shafts rotatively mounted on said support at right angles to the driving shaft and at opposite sides of said crank, the shafts of each pair having the same axis and disposed at opposite sides of the driving shaft, four vertical wind wheels secured respectively to said transverse shafts, and means for imparting rotation in like direction from said transverse shafts to said driving shaft.

5. The combination with the tower, of a support rotative thereon in a horizontal plane, a longitudinal driving shaft rotatively mounted on said support and intersecting the axis of revolution of the support and having at the axis of revolution a crank, a pitman pivoted to said crank, two pairs of transverse horizontal shafts rotatively mounted on the support at right angles to the driving shaft and at opposite sides of the crank, the shafts of each pair having the same axis and disposed at opposite sides of the driving shaft, means for imparting rotation in a like direc-

tion from said transverse shafts to said driving shaft, and four vertical wind wheels secured respectively to said transverse shafts, the blades of each wheel of a pair being inclined relative to the face of the wheel oppositely to the blades of the wheel having the same axis.

6. The combination with the windwheel support rotative in a horizontal plane, of a windwheel rotatively mounted on said support, a vane pivoted on said support to swing on a vertical axis from a position in which the windwheel will be swung with said support into the wind to a position in which the support will be swung so as to throw the windwheel out of the wind, automatic means for locking the vane in the second position, manually operated means for releasing the vane from said locking means, a member pivoted to swing vertically on said support, a weight carried by said member, a pulley mounted on said support, a flexible device connected at one end to said member and passing over said pulley, and means connected with the other end of said flexible device for swinging the vane to said first named position.

7. The combination with the windwheel support rotative in a horizontal plane, of a windwheel rotatively mounted on said support, a vane pivoted on said support to swing on a vertical axis and having a horizontal arm disposed at an angle to said vane, automatic means for locking the vane in a position in which the support will be swung so as to throw the windwheel into the wind, manually operated means for swinging the vane into engagement with said locking means, manually operated means for releasing the vane from said locking means, a pulley mounted on said support, a flexible device mounted to run on said pulley, and connected at one end to said arm, a vertically movable weight, and means connected with the other end of said flexible device for supporting said weight.

8. The combination with the windwheel support rotative in a horizontal plane, of a windwheel rotatively mounted on said support, a vane pivoted on a vertical axis on said support and movable from a position in which the support will be swung so as to throw the windwheel into the wind to a position in which the windwheel will be thrown out of the wind, automatic means for locking the vane in the latter named position, manually operated means for swinging said vane into engagement with said locking means, manually operated means for releasing the vane from said locking means, a member pivoted to said support so as to swing vertically, a weight carried by said member, a pulley mounted on the support, a flexible device connected at one end to said member and passing upwardly therefrom over said

- pulley, and means connected with the other end of said flexible device by which the vane is swung by said weight to the first named position.
5. The combination with the windwheel support rotative in a horizontal plane, of a windwheel rotatively mounted on said support, a vane pivoted on a vertical axis on said support and having a horizontal arm extending at an angle to the vane and by which the vane may be swung to a position in which the support will be swung so as to throw the windwheel into the wind, the vane being movable to a position in which the windwheel will be thrown out of the wind, releasable automatic means for locking the vane in the latter named position, manually operated means for releasing the vane from said locking means, manually operated means for swinging the vane into engagement with said locking means, a member pivoted to swing vertically on said support, a weight carried by said member, a pulley mounted on said support, and a flexible device secured at one end to said member and passing upward therefrom over said pulley and secured at the other end to said arm.
10. The combination with the support rotative in a horizontal plane, of a windwheel rotatively mounted on said support, an auxiliary vane secured to said support so as to be normally flatwise to the wind, a vane pivoted to the support on a vertical axis and movable from a position in which the support will be swung so as to throw the windwheel into the wind to a position in which the windwheel will be thrown out of the wind, a member pivoted so as to swing vertically on said support, a weight carried by said member, a pulley mounted on said support, a flexible member mounted so as to run on said pulley and secured at one end to said member, and means connected with the other end of said flexible member for swinging the pivoted vane to the position first named.
15. The combination with the support rotative in a horizontal plane, of a windwheel rotatively mounted on said support, an auxiliary vane secured to said support so as to swing on a vertical axis from a position in which the windwheel will be thrown into the wind to a position in which the windwheel will be thrown out of the wind, releasable automatic means for locking the pivoted vane in the last named position, manually operated means for releasing the pivoted vane from said locking means, manually operated means for swinging the pivoted vane into engagement with said locking means, a member pivoted to said support so as to swing vertically, a weight carried by said member, a pulley mounted on said support, a flexible device mounted so as to run on said pulley and secured at one end to the said member, and means connected with the other end of
- the flexible device for swinging the pivoted vane into the first named position.
12. The combination with the support rotative in a horizontal plane, of two pairs of windwheels rotatively mounted on said support at opposite sides of a vertical plane intersecting transversely to the support the axis of revolution of the support, the windwheels of each pair being disposed one in front of the other and at opposite sides of a vertical plane intersecting the axis of revolution at right angles to the other intersecting plane, a vane pivoted on a vertical axis on said support in the said transverse vertical plane and movable from a position in which the support will be swung so as to throw the wind wheels into the wind to a position in which the windwheels will be thrown out of the wind, and yielding means for normally swinging the vane into the first named position.
13. The combination with the support rotative in a horizontal plane, of two pairs of wind wheels rotatively mounted on said support at opposite sides of a vertical plane intersecting transversely to the support the axis of revolution of the support, the windwheels of each pair being disposed one in front of the other and at opposite sides of a vertical plane intersecting the axis of revolution at right angles to the other intersecting plane, a movable member, means by which rotation of said windwheels imparts movement in like direction to said member, a vane pivoted on a vertical axis on said support in said transverse vertical plane and movable from a position in which the windwheels will be held in the wind to a position in which the windwheels will be thrown out of the wind, and yielding means for normally swinging the vane into the first named position.
14. The combination with the support rotative in a horizontal plane, of two pairs of wind wheels rotatively mounted on said support at opposite sides of a vertical plane intersecting transversely to said support the axis of revolution of the support, the windwheels of each pair being disposed one in front of the other and at opposite sides of a vertical plane intersecting the axis of revolution at right angles to the other intersecting plane, a movable member, means by which rotation of the wind wheels imparts movement in like direction to said movable member, an auxiliary vane secured to said support parallel with said second named plane, a vane pivoted to the support on a vertical axis and movable from a position in which the windwheels will be thrown into the wind to a position in which the windwheels will be thrown out of the wind, and means for normally swinging said vane into the first named position.
15. The combination with the support rotative in a horizontal plane, of two pairs of windwheels rotatively mounted on said support at opposite sides of a vertical plane

- intersecting transversely to the support the axis of revolution of the support, the wind-wheels of each pair being disposed one in front of the other and at opposite sides of a 5 vertical plane intersecting the axis of revolution at right angles to the other intersecting plane, a movable member, means by which rotation of said windwheels imparts like direction of movement to said movable member, 10 an auxiliary vane secured to the support parallel with said second named plane, a vane pivoted to the support on a vertical axis located in the transverse plane and movable from a position in which the windwheels will 15 be thrown into the wind to a position in which the windwheels will be thrown out of the wind, automatic means for locking the pivoted vane in the second named position, manually operated means for releasing the pivoted 20 vane from said locking means, manually operated means for swinging the pivoted vane into engagement with the locking means, and means for normally swinging the pivoted vane into the position first named.
- 25 16. The combination with the support rotative in a horizontal plane, of two pairs of rotary horizontal shafts mounted at opposite sides of a vertical plane intersecting transversely to said support the axis of revolution 30 of said support, the shafts of each pair being disposed at opposite sides of a vertical plane intersecting the axis of revolution at right angles to the other plane, the shafts of each pair having the same axis, four wind wheels 35 secured respectively upon said rotary shafts, a movable member, means for imparting by means of rotation of said shafts movement in like direction to said movable member, a vane pivoted on a vertical axis on said support 40 in the transverse plane, and movable from a position in which the wind wheels will be held in the wind to a position in which the windwheels will be thrown out of the wind,
- releasable means for holding the vane in the last named position, means for normally 45 swinging the vane into the first named position, and an auxiliary vane secured to the support parallel with the second named plane.
17. The combination with the support rotative in a horizontal plane, of two pairs of 50 rotary shafts mounted on said support at opposite sides of a vertical plane intersecting transversely to said support the axis of revolution of the support, the shafts of each pair being located at opposite sides of a vertical 55 plane intersecting the axis of revolution at right angles to the other plane, four wind wheels mounted respectively on said shafts, a driving shaft disposed horizontally in the latter named plane and having a crank at the 60 intersection of the two planes, means for imparting rotation from said four shafts to said driving shaft, a pitman pivoted to said crank, an auxiliary vane secured to the support at one side of the transverse plane and parallel 65 with the other plane, a vane pivoted to the support on a vertical axis located in the transverse plane and movable from a position in which the windwheels will be thrown out of the wind, automatic 70 means for locking the pivoted vane in the last named position, manually operated means for releasing the pivoted vane from the locking means, manually operated means for 75 swinging the pivoted vane into engagement with the locking means, and means for normally swinging the pivoted vane into the first named position.

In testimony whereof I affix my signature 80 in presence of two witnesses.

ALBERT. F. GEORGE.
